DUST HOOD

George J. Pipher, Reading, Pa., assignor to Williamson Products, Inc., Reading, Pa., a corporation of Pennsylvania

Application June 6, 1950, Serial No. 166,333

3 Claims. (Cl. 128—141)

This invention relates to a dust hood such as used for protecting personnel against heavy concentrations of dust, including pneumoconiosis-producing dusts, and, more particularly, to a respirator mounting means for detachably supporting a respirator on the window of the dust hood.

A common expedient for the mounting of a respirator on the window of a dust hood is to puncture a hole through the transparent plastic window, collapse the respirator, and thereafter force it through the hole until the neck portion of the respirator coincides with the hole in the window. This expedient is unsatisfactory, particularly for respirators with large face pieces or relatively small neck portions, since forcing of the respirator into place generally causes tearing of the peripheral portion of the hole in the plastic window, thereby causing leakage of dust therethrough.

An object of the present invention is to provide a novel means for detachably mounting a respirator on the window of a dust hood which is devoid of the above named disadvantages.

A more specific object of the present invention is to provide mounting means for easily and quickly mounting, in a readily detachable manner, a respirator in the window of a dust hood, which mounting means will snugly embrace the respirator in a substantially dust-free manner, and which allows removal or replacement of the respirator without damage to the window.

Other objects and advantages of the present invention will be apparent from a study of the following description, taken with the accompanying drawing wherein:

Fig. 1 is a front, elevational view of a dust hood having, in its window, a respirator mounting means embodying the principles of the present invention;

Fig. 2 is a cross-sectional view taken along line II—II of Fig. 1;

Fig. 3 is a plan view of a frame member for clampingly supporting the respirator as shown in Figures 1 and 2.

Fig. 4 is a plan view of the window shown in Figures 1 and 2.

Fig. 5 is a plan view, with parts shown broken away, of a modified form of frame member slightly different from that shown in Figure 3.

Fig. 6 is a fragmentary plan view of further modified form of frame member, and,

Fig. 7 is a plan view of a differently shaped window showing a still further modified form of frame member.

Fig. 1 is a front, elevational view of the dust hood having the respirator mounted on the window, and a fragmentary plan view of a modified form of frame member.

Fig. 2 is a fragmentary plan view of further modified form of frame member.

Fig. 3 is a plan view of a frame member for clampingly supporting the respirator as shown in Figures 1 and 2.

Fig. 4 is a plan view of the window shown in Figures 1 and 2.

Fig. 5 is a plan view, with parts shown broken away, of a modified form of frame member.

Fig. 6 is a fragmentary plan view of further modified form of frame member.

Fig. 7 is a plan view of a differently shaped window showing a still further modified form of frame member.

Referring more particularly to Figures 1 and 2, numeral 1 denotes a dust hood of canvas or other suitable fabric or material having, at the front thereof, an opening of polygonal shape along the perimeter of which is sewn a strip 2 of similar material. The outer perimetrical edge of strip 2, with the exception of the top horizontal portion, is sewn to the hood and overlies a marginal portion 3 of the hood, thereby providing a pocket.

A flap 4 is sewn along its top edge portion over the marginal portion 3 and is detachably fastened to the frame member by snap fastener elements 5.

Into the pocket described above there is inserted a window supporting, frame member 6, preferably of hard fibrous material and having two somewhat U shaped portions 6a and 6b whose extremities are detachably fastened together by male and female snap fastening elements 7. Portions 6a and 6b are pivotally mounted together at pivot 8 so as to enable opening of the frame member when the fastener elements are detached. Extensions or jaw-like arms 10 and 11 are integrally formed on portions of 6b and 6a, respectively. The upper extremities 9 of arms 10 and 11 overlap slightly. The opening defined by extensions 10 and 11 corresponds, in shape, to the intermediate neck portion of the respirator, of smallest cross section.

Into the pocket described above there is inserted a window supporting, frame member 6, preferably of hard fibrous material and having two somewhat U shaped portions 6a and 6b whose extremities are detachably fastened together by male and female snap fastening elements 7. Portions 6a and 6b are pivotally mounted together at pivot 8 so as to enable opening of the frame member when the fastener elements are detached. Extensions or jaw-like arms 10 and 11 are integrally formed on portions of 6b and 6a, respectively. The upper extremities 9 of arms 10 and 11 overlap slightly. The opening defined by extensions 10 and 11 corresponds, in shape, to the intermediate neck portion of the respirator, of smallest cross section.

The respirator may be of any well-known type such as one including a face piece to snugly fit the face of the wearer, and a perforated cover 12 screw threaded to a filter containing cup 13 enclosing a filter of any well-known type, such as a hollow filter with a disc attached thereto whose marginal edge portion is sealingly held in place by the cover 12. The respirator may also include an exhalation valve 14. It should be noted, however, that other types of respirators having differently shaped necks may be similarly mounted in which case, of course, the shape of the opening defined by extensions 10 and 11 would be somewhat different.

Frame member 6 is provided with a plurality of snap fastener elements 15 which are adapted to be fastened to corresponding snap fastener elements 5 provided on flap 4. It will be noted that the top horizontal portion of strip 2 which extends underneath flap 4 has, in alternate positions, snap fastener elements and holes so that certain of the fastener elements of the flap are attachable to corresponding ones of the strip portion while others extend through the holes in the top strip portion so as to be attachable to

the corresponding fastener elements 15 on the frame member 6. Thus the frame member is detachably secured to the flap 4 and at the same time the flap is detachably secured to the top horizontal portion of strip 2.

A window 16, illustrated in Figure 4 and preferably made of transparent plastic material is slidable into the pocket behind the frame member 6 as shown more clearly in Figure 2. Window 16 has a cut-out portion 16a in registry with the opening defined by extensions 10 and 11.

In operation, when it is desired to mount the respirator on frame member 6, snap fastener elements 7 are detached and frame member portion 6a and 6b are spread apart about their common pivot 8 so as to permit insertion of the respirator between the jaw like extensions 10 and 11. The respirator is introduced between the jaw-like arms 10 and 11 while frame member 6 is opened and partially inserted in the pocket defined by strip 2 and marginal portion 3. Portions 6a and 6b are then brought together with extensions 10 and 11 clampingly engaging the neck portion of the respirator in a snug, substantially dust-tight manner. The snap fastener elements 7 are then secured together. Window 16 is then inserted behind the frame member and the top flap 4 is fastened to the top portion of strip 2 as well as to the fastener elements 15 on the frame member 6.

Figure 5 shows a modification of the frame member shown in Figure 3 wherein such member, instead of comprising two pivotally mounted portions which form a polygon is in the form of a single piece of polygonal shape having fastener elements 15. The integral arm 10 is the same as that shown in Figure 3, however, the complementary arm 11, instead of being integral with the frame member is pivotally mounted thereto at pivot 18 and is detachably secured to the extremity of the arm 10 by snap fastener elements 19. In order to insert the respirator, snap fastener elements 19 are detached and arm 11 is swung outwardly to the position shown in dash and dot lines. Figure 6 shows a still further modification of the frame member wherein the jaw-like arms 20 and 21 are pivotally mounted at pivots 22 and 23, respectively, on the frame member and are detachably secured together by male and female snap fastener elements 24. In order to insert the respirator, fastener elements 24 are detached and arms 20 and 21 are pivotally swung outwardly to the dot and dash line positions.

Figure 7 shows a modification of the window and frame member wherein the periphery of the frame member 25 may be sewn to the hole-defining, edge portion of the front opening of the hood and wherein the frame member 25 may be somewhat elliptical, having an arm or extension 25b pivotally mounted at pivot 26 and having pairs of fastener elements 27 and 28 for attaching the arms together to form a substantially dust-tight closure element for the respirator. The dash and dot lines show the position to which arm 25b can be swung after the fastener elements are detached in order to permit insertion of the respirator.

Thus, it will be seen that I have provided an efficient dust hood including a readily detachable respirator mounting which permits the mounting of a respirator in the window of the dust hood in a dust-tight manner and which will allow easy and quick replacement of the respira-

tor or removal thereof, in which latter event a window without a notched out portion 6a may be inserted.

While I have illustrated and described certain specific embodiments of my invention, it will be apparent that these are by way of illustration only, and that various changes and modifications may be made within the contemplation of my invention and within the scope of the following claims.

I claim:

1. A dust hood having a front opening, a strip whose outer edge is sewed about a substantial portion of said opening to provide a pocket, a window having a shape corresponding to said opening and which is insertible in said pocket, said window having a cut-out portion at the lower central edge portion thereof, a polygonally shaped frame member comprising two portions

15 pivotally mounted together and having detachable fastening means thereon for attaching their extremities together and having integral, jaw-like arm portions defining an opening therebetween for snugly embracing an intermediate neck portion of a respirator, thereby supporting the respirator within said cut-out portion in a substantially dust-tight manner.

2. A dust hood having a front opening, a frame member detachably secured in registry with said

30 opening and including a pair of jaw-like extensions, of substantially semi-circular shape so that the extensions define therebetween a substantially round hole for snugly embracing a portion of the neck of a respirator to be mounted there-

35 in, and a window having a notched-out portion in registry with said hole defined by said extensions and in which said respirator is supported, said frame member comprising two pivotally connected parts whereby said extensions may be moved apart to facilitate introduction of the respi-

40 rator therebetween.

3. A dust hood having a front opening, a frame member having a shape corresponding to that of said opening and held in registry therewith,

45 said frame member including an extension adapted to snugly embrace a portion of an intermediate neck of a respirator so as to support the respirator in a substantially dust-tight manner,

50 a window having a shape corresponding to that of said opening and superimposed on said frame member, said window having a notch registering with said neck of the respirator, and detachable fastening means on said frame mem-

55 ber for holding said extension in the respirator-embracing position and, when detached, allowing enlargement of the respirator neck supporting opening defined partially by said extension to facilitate introduction or removal of the respirator within the frame member and for pro-

60 viding a substantially dust-tight joint with the respirator.
